W. K. MASON & C. L. DONOHO,
HEATER FOR RADIATORS,
APPLICATION FILED JAN. 15, 1917.

1,235,828.

Patented Aug. 7, 1917.

UNITED STATES PATENT OFFICE.

WILLIAM K. MASON AND CHRIS L. DONOHO, OF CAMBRIDGE, MASSACHUSETTS.

HEATER FOR RADIATORS.

1,235,828.

Specification of Letters Patent.

Patented Aug. 7, 1917.

Application filed January 15, 1917. Serial No. 142,554.

To all whom it may concern:

Be it known that we, WILLIAM K. MASON and CHRIS L. DONOHO, citizens of the United States, residing at Cambridge, in the county of Middlesex and State of Massachusetts, have invented new and useful Improvements in Heaters for Radiators, of which the following is a specification.

This invention relates chiefly to radiators for household use, and has for its object to enable an ordinary radiator such as is commonly heated by steam or hot water, to be utilized as a part of a complete heating apparatus, preferably portable, the apparatus as a whole including an ordinary radiator, a boiler located below the base portion of the radiator and connected with said base portion by flow and return conduits, means supporting said boiler spaced above a floor, and a burner located under the boiler and arranged to direct its flame against the under side of the boiler, said base portion, the flow and return conduits, and the boiler constituting a water-circulating system adapted to supply vapor to the radiator.

Of the accompanying drawings forming a part of this specification,—

Figure 1 is a side elevation of a heating apparatus embodying our invention.

Fig. 2 is an end elevation of the same.

Fig. 3 is a section on line 3—3 of Fig. 2.

Fig. 4 is a plan view of the boiler.

Fig. 5 is a section on line 5—5 of Fig. 4.

The same reference characters indicate the same or similar parts in all of the figures.

In the drawings, 12 represents a common type of steam or hot water radiator composed of a plurality of upright sections connected at their lower ends to form a water-containing base portion 12^a, and at their upper ends to permit the passage of steam or vapor from section to section.

The base portion of the radiator presents heat-radiating surfaces of relatively small area, and the upper portion formed by the said sections presents heat-radiating surfaces of relatively large area. The base portion 12^a is provided with the usual legs 13 and with means at its end portions for engagement with a flow conduit 15, and a return conduit 14 which communicate with the base 12^a at points above the bottom of the latter, so that a relatively shallow accumulation of water may be maintained in the base portion, as shown by Fig. 3. The said flow and return conduits, so far as their relation

to the radiator is concerned, are the same as in the ordinary steam or hot water heating apparatus. The conducting capacity of the flow conduit 15 is greater than that of the return conduit, for a purpose hereinafter explained. 16 represents an elongated boiler having top and bottom sides of considerably greater area than its vertical edges, so that the boiler is adapted to hold and conduct a relatively shallow body or accumulation of water, the top side of the boiler preferably presenting the outline shown by Fig. 4. The end portions of the reservoir are connected with the conduits 14 and 15, the boiler being coupled to and spaced from the base portion 12^a of the radiator by said conduits, as shown by Figs. 1, 2 and 3.

The boiler and radiator are supported at a sufficient height above the floor to permit the location, under the boiler, of a burner 17, which is preferably a blue flame oil burner, which may be carried and guarded by the supporting means, hereinafter described and is arranged to direct its flame against the under side of the boiler. Preferably, the said under side is provided with a concave portion 16^a against which the burner flame impinges and by which it is deflected radially and somewhat downwardly.

The said supporting means may include a suitable curb 19, forming the upright walls of a heat-confining casing around the burner 17 and provided with an opening in one side to permit access to the burner, said opening being covered by a movable door 20.

The base portion 12^a of the radiator and the boiler 16 are charged with water, as indicated by Fig. 3, there being preferably only sufficient water in the base portion 12^a to cause the circulation hereinafter described. The effect of the heat generated by the burner is to heat the water and cause a circulation thereof, as indicated by arrows in Fig. 3. The water heated in the boiler is caused, by the difference between the conducting capacities of the conduits 14 and 15, to flow in one direction in the boiler toward the flow conduit 15, and to flow in the opposite direction in the base portion of the radiator, and continuously give off vapor, which fills the upper portion of the radiator above the base 12^a, so that the radiator becomes active.

The boiler is preferably provided with

flanges 24 which are flush with the bottom of the boiler and constitute, with said bottom, a cover for the curb 19, adapted to intercept any smoke which may be caused by imperfect combustion when the burner is first lighted, and prevent the smoke from soiling the radiator. The said cover and curb constitute a casing adapted to confine flames and heat under the reservoir, so that there is no danger of igniting dress skirts, etc., which may be near the structure. Said casing also stabilizes the flame by preventing air currents from impinging horizontally upon it. The radiator legs rest on the flanges 24, as shown by Figs. 1 and 2. The casing 19 is preferably provided with a bottom 23 having an opening 26 to admit air upwardly to support combustion. The ends of the casing may be provided with outlets 27 for hot air and products of combustion, these being preferably located under the projecting end portions 16^b of the boiler. The oil reservoir, the burner, and the oil-conducting means connecting said parts, may be constructed and arranged in any suitable way, the structure, including said parts, here represented somewhat conventionally, being well known in blue flame oil stoves, said structure being provided with means, including a stem 28, for regulating the flow of oil. It is obvious that the radiator may be entirely filled with water, if desired, although we do not recommend this. We find it preferable to maintain the water level below the top of the base portion, substantially as indicated by Fig. 3, so that vapor is free to rise from all portions of the surface of the moving body of water.

We do not limit ourselves to an oil burner and may use a burner for gas or other suitable fuel.

We have found that the above-described heating apparatus is both efficient and economical. The entire apparatus as illustrated, constitutes a self-contained heat-generating and radiating structure adapted to be transported from place to place, the supporting means being preferably provided with casters 22. An oil reservoir 23 may be connected with the structure as indicated by Fig. 2 to supply oil to the burner.

It will now be seen that the boiler, the flow and return conduits, and the radiator, constitute a water-circulating and heat-radiating structure adapted to contain a limited charge of water which fills the boiler and the said conduits, and only partly fills the base portion of the radiator, the level of said charge being maintained at a predetermined height and below the vapor-receiving portion of the radiator, because the delivering end of the flow conduit and the intake end of the return conduit are at substantially the same elevation at their points

of connection with the radiator. The delivering end of the return conduit and the intake end of the flow conduit are also at the same elevation at their points of connection with the boiler. The height of said structure is therefore reduced to the minimum, which is an important advantage. The difference between the conducting capacities of the flow and return conduits causes a continuous flow of the charge of water in one direction through the boiler to receive heat, and in the opposite direction through the base portion of the radiator to continuously give off vapor to the vapor-receiving portion of the radiator.

It will also be seen that the curb 19 constitutes the base of a self-contained portable structure, and that the boiler 16, the radiator, and the conduits 14 and 15, constitute a superstructure which is applicable as a single part to said base, the radiator being rigidly connected with the boiler by said conduits, and the radiator legs 13 being held by the conduits firmly seated on the portions of the boiler formed by the flanges 24. The parts of said superstructure may be conveniently assembled before the application of the superstructure to the base. The assemblage of the base and superstructure forms a substantially closed casing whereof the boiler is the top, said casing guarding the burner flame.

We claim:

1. In a portable heat generator and radiator the combination of an elongated boiler, flow and return conduits extending from opposite ends of the boiler, a radiator coupled to the boiler by said conduits and having an elongated water-containing base portion substantially parallel with the boiler, and a vapor-containing upper portion, a base supporting the boiler and radiator in substantially horizontal positions, and a burner in said base arranged to direct its flame against the bottom of the boiler, the delivering end of the flow conduit and the intake end of the return conduit being at substantially the same elevation at their points of connection with the radiator, and arranged to maintain the level of a charge of water, filling said boiler and conduits, at a predetermined level below said vapor-containing portion, the delivering end of the return conduit and the intake end of the flow conduit being at substantially the same elevation at their points of connection with the boiler, and the conducting capacity of one conduit being greater than that of the other, whereby, when the boiler is heated, said charge is caused to flow in one direction through the boiler and receive heat, and in the opposite direction through the base portion of the radiator and give off vapor.

2. A portable heat-generating-and-radiat-

ing structure comprising a curb having an open top and constituting the base portion of the structure, a burner within the curb, and a superstructure applicable as a single 5 part to the curb and composed of a boiler formed to cover the upper end of the curb, a radiator above the boiler, and flow and return conduits of different capacities connecting opposite end portions of the boiler 10 with opposite end portions of the radiator.

3. A portable heat-generating-and-radiating structure comprising a curb having an open top and constituting the base portion of the structure, a burner within the curb, 15 and a superstructure applicable as a single part to the curb and composed of a boiler formed to cover the upper end of the curb, a radiator above the boiler, the flow and return conduits of different capacities connecting opposite end portions of the boiler with 20 opposite end portions of the radiator, the radiator being provided with downwardly

projecting legs which are confined by said conduits against portions of the boiler.

4. A portable heat-generating-and-radiating structure comprising a curb having an open top and constituting the base portion of the structure, a burner within the curb, and a superstructure applicable as a single 25 part to the curb and composed of a boiler formed to cover the upper end of the curb, a radiator above the boiler, and flow and return conduits of different capacities connecting opposite end portions of the boiler 30 with opposite end portions of the radiator, the boiler being provided with flanges at its lower portion, and the radiator being provided with downwardly projecting legs which are confined by said conduits against 35 said flanges.

In testimony whereof we have affixed our signatures.

WILLIAM K. MASON.
CHRIS L. DONOHO.
